United States Patent Office

Des. 192,641
Patented Apr. 24, 1962

192,641

METRONOME HOUSING

William H. Harkins, Lexington, Mass., assignor to Connecticut Technical Corporation, Hartford, Conn., a corporation of Connecticut

Filed Aug. 16, 1961, Ser. No. 66,371

Term of patent 14 years

(Cl. D42—7)

FIG. 1

FIG. 2

FIG. 1 is a perspective view of a metronome housing showing my new design.

FIG. 2 is a top plan view thereof.

I claim:

The ornamental design for a metronome housing or similar article, as shown.
